CLAIM

The ornamental design for a toilet bowl deodorant holder, as shown and described.

DESCRIPTION

FIG. 1 is a perspective view of a toilet bowl deodorant holder showing my new design;

FIG. 2 is a top plan view thereof;

FIG. 3 is a front elevational view thereof;

FIG. 4 is a rear elevational view thereof;

FIG. 5 is a side elevational view thereof, the opposite side being a mirror image;

FIG. 6 is a bottom plan view thereof; and

FIG. 7 is a second embodiment thereof, the second being identical to the first except for the shape of the hanger as seen from the side.

FIG. 1

FIG. 2

FIG. 3

FIG. 4

FIG. 5

FIG. 6

FIG. 7
